ATTORNEY

UNITED STATES PATENT OFFICE

CECIL W. COTTON, OF TULSA, OKLAHOMA, ASSIGNOR TO WALES DOVE-HERMISTON CORPORATION, OF NEW YORK, N. Y.

TRAVELING POURING POT FOR PIPE COATINGS

Application filed June 14, 1930. Serial No. 461,139.

My invention relates to pipe coating machines and more particularly to a device of that character for pouring heated asphalt or similar preservative material on pipe lines such as conduits used for conveying petroleum products to resist deterioration of such lines when buried in the ground.

In ordinary practice the asphalt is poured on the pipe with pails, which is obviously a slow process accompanied with danger of injury to the workman, when the coating is applied in heated and molten condition.

The principal objects of my invention are, therefore, to expedite such operations and to reduce the danger of harm to the operator by providing a portable device adapted to be moved along the pipe and including means for spreading the coating on the pipe string in desired quantities.

20 In accomplishing these and other objects of my invention I have provided improved details of structure, the preferred form of which is illustrated in the accompanying drawings, wherein:

25 Fig. 1 is a perspective view of a traveling pouring pot, embodying my invention mounted on a pipe line.

Fig. 2 is a central longitudinal section of the device.

30 Fig. 3 is a central cross section of the pouring pot illustrating, particularly, the control gate.

Referring more in detail to the drawings: 35 1 designates a pipe line and 2 a traveling pouring pot adapted to be moved therealong and including a pair of spaced cross sills 3 and 4 preferably comprising inverted channel members having horizontal web portions 5 and side flanges 6.

40 A series of aligning apertures 7 in the side flanges provide for adjustably mounting bearing brackets 8 between said flanges on bolts 9, extended through the brackets and flanges. Each bracket includes spaced depending ears 10 for receiving therebetween a roller 11 rotatably mounted on a shaft 12 extending transversely through the ears, the brackets on opposite ends of the sills being formed to converge inwardly so that the rollers will be on an approximately radial

line with the axis of the pipe when mounted thereon.

Spaced longitudinal frame members 13 and 14, formed of angle bars and connecting the cross members near their ends, include 55 horizontal portions 15 secured to the webs of the cross members by bolts 16. The outer ends of the frame members are bent upwardly at right angles to the horizontal portions to form standards 17 and 18 for supporting 60 a vat or receptacle 19 adapted to contain the coating liquid.

The receptacle preferably includes front and rear walls 21 and 22, an inclined arcuate bottom 23 terminating in side walls 24, and a 65 cover 25 having an outer vertical flange 26 and an inwardly directed and downwardly inclined flange 27 covering the greater portion of the vat, so that pouring of liquid through the filler opening 28 defined by the 70 inclined flange will be facilitated, and splashing of liquid from the receptacle will be prevented.

Fumes and smoke which may collect in the receptacle when hot liquid is employed are 75 conducted therefrom through a vertical conduit 29, fixed in an opening 30 in the inclined flange near its upper edge.

The rear wall 22 is provided adjacent its bottom with a rectangular outlet opening 31 80 surrounded by an outwardly extending flange 32, the outlet opening being controlled by a gate 33 vertically slidable between guide flanges 34 secured by welding or the like to the inner face of the rear end wall. 85

Fixed to the outer face of the end wall 22 near its upper center are spaced brackets 35 projecting above the upper edge of the receptacle for pivotally mounting a gate control lever 36 supported therebetween on a fulcrum pin 37. The control lever extends over the longitudinal center of the receptacle and projects over the front wall 21 to form a handle portion provided with an aperture 38 adapted to align with a series of apertures 39 in an upwardly extending arcuate bar 40, fixed to the front end wall by welding or the like, a pin 41 retaining the lever in adjusted position.

95 A bar 42 connecting the control lever and 100

the gate 33 is pivotally secured by a pin 43 to an angle bracket 44 fixed to the control gate, the upper end of the bar being pivotally secured to the control lever by a bolt 45.

5 In order to equally spread the liquid flowing from the vat over the pipe to be coated, a spreader spout 46 is preferably pivotally mounted over the outlet flange 32 by a bolt 47 extended transversely through the side 10 walls of the flanged opening and through a neck portion 48 of the spout.

The spout preferably includes a solid bottom wall 49, and an upper wall 50 spaced from the bottom wall by downwardly tapering side walls 51 and slotted at its outer end as indicated at 52, each finger 53 formed by the slits being maintained in adjusted relation to the bottom wall by a bolt 54 extending through the finger and lower wall and 15 having a thumb nut 55 threaded thereon for facilitating adjustment of the mouth opening 56.

In its preferred form the lower end of the spout is shaped arcuately to more nearly conform to the curvature of the pipe, and the mouth of the spout is adjustably supported relative to the pipe by a chain 57 anchored to the spout. The opposite end of the chain is attached to a hook 58 fixed centrally in a 20 horizontal cross bar 59 secured to the rear standards by means such as cap screws 60 and having end portions projecting equally beyond the opposite sides of the frame.

A duplicate cross bar 61 is secured to the 25 front standards, and aligning openings 62 are provided in the cross bars adjacent their ends for receiving longitudinal bars 63, preferably formed of pipe.

Threaded on the front end of each longitudinal bar is a pipe union 64 for connecting an upwardly directed arm 65, having a forwardly extending handle portion 66, so that the device may be manually propelled by an operator walking on the pipe.

45 An elbow 67 is threaded on the rear end of each longitudinal bar to receive a handle bar 68 extending outwardly and horizontally from the device to enable a workman, walking on the ground, to readily push the apparatus along the pipe line.

In pouring preservative on a pipe line with a device constructed and assembled as described, and mounted on a line, the asphalt or other material used is preferably heated 55 and supplied to the vat through the filler opening after the control gate has been lowered to closed position.

The gate is then adjusted and locked in desired open position by elevating the control lever and inserting the pin 41 through one of the series of apertures 39, and the fingers on the spreader spout are also individually adjusted to control the flow of liquid from the spout.

65 Due to the very viscous nature of the coat-

ing material commonly used on pipe, it is desirable to adjust the fingers adjacent the side edges of the spout to a relatively wide open position to permit a sufficient amount of material to flow from the spout for covering the 70 sides and lower surface of the pipe. The intermediate fingers of the spout, however, are more closely adjusted as, otherwise, a heavier layer than required would be applied to the upper pipe surface and result in unnecessary waste of coating material. 75

As the apparatus is moved along the conduit, the liquid is distributed over the pipe more evenly and with less danger of injury to the workman than has been possible with 80 the methods commonly employed.

What I claim and desire to secure by Letters Patent is:

1. In a device of the character described, a portable frame, a receptacle carried by the frame having an inclined bottom, an end wall on the receptacle having an outlet opening adjacent the lower end of said bottom, a spreader spout attached to the receptacle adjacent said opening having a solid lower wall and a coextensive slotted upper wall, and means for independently adjusting each slotted portion of the upper wall in spaced relation with the lower wall. 85

2. In a device of the character described, a portable frame, a receptacle carried by the frame having an inclined bottom, an end wall on the receptacle having an outlet opening, a gate mounted in adjustable sliding relation with said opening, a spreader spout attached to the receptacle adjacent said opening, having a solid lower wall and a slotted upper wall, and independent means for adjusting each slotted portion of the upper wall in spaced relation with the lower wall. 90

3. In a device of the character described, a frame adapted to be moved longitudinally upon a conduit, a receptacle carried by the frame having an arcuate inclined bottom, end walls on the receptacle, one of said walls having an outlet opening, an inwardly and downwardly directed flange surrounding the upper edge of the receptacle, and a spreader spout pivotally attached to the receptacle adjacent the outlet opening, and having a series of 110 individually adjustable mouth portions. 110

4. In a device of the character described, a frame adapted to be moved longitudinally upon a pipe, a receptacle carried by the frame having an outlet opening, a rearwardly extending rectangular flange surrounding said opening, a spreader spout pivotally attached to said flange, and having an arcuate mouth complementary to the curved surface of the pipe, said spout having a slotted upper wall, and a solid bottom wall, and means for adjusting the slotted portions independently in spaced relation with the bottom wall. 120

In testimony whereof I affix my signature.

CECIL W. COTTON.
